FIG. 1

FIG. 2

FIG. 3

FIG. 4

FIG. 5

FIG. 6

FIG. 7

FIG. 8

FIG. 9

FIG. 10

FIG. 1 is a top plan view of one embodiment of a link chain for a bracelet or the like showing my new design wherein the center offset portion consists of three equally proportioned rows;

FIG. 2 is a top plan view on an enlarged scale of a single link thereof of FIG. 1;

FIG. 3 is an end elevational view taken from the left hand end of FIG. 2;

FIG. 4 is an end elevational view taken from the right hand end of FIG. 2;

FIG. 5 is a side elevational view of the link of FIG. 2;

FIG. 6 is a top plan view of a modified form of the link chain of FIG. 1 wherein the center offset portion consists of three rows, the center row being narrow and separated from the adjacent wider rows by deep, wide grooves;

FIG. 7 is a top plan view on an enlarged scale of a single link thereof of FIG. 6;

FIG. 8 is an end elevational view taken from the left hand end of FIG. 7;

FIG. 9 is an end elevational view taken from the right hand end of FIG. 7; and

FIG. 10 is a side elevational view of the link of FIG. 7.

This is a continuation of design applications Ser. Nos. 7,996 and 7,998, both filed July 26, 1967 and both now abandoned.

I claim:

The ornamental design for a link chain for a bracelet or the like, as shown and described.
